(57) **CLAIM**

The ornamental design for a cup holder for seating, as shown and described.

DESCRIPTION

FIG. 1 is a front elevation view of a first embodiment of my new design for a cup holder for seating; FIG. 2 is a rear elevational view thereof; FIG. 3 is a left side view thereof; FIG. 4 is a right side view thereof; FIG. 5 is a top plan view thereof; FIG. 6 is a bottom plan view thereof; FIG. 7 is a bottom perspective view thereof; FIG. 8 is a top perspective view thereof; FIG. 9 is a second top perspective view thereof; FIG. 10 is a third top perspective view thereof; FIG. 11 is a second bottom perspective view thereof, shown with a cooler attached thereto for clarity of disclosure; FIG. 12 is a front elevation view of a second embodiment of my new design for a cup holder for seating; FIG. 13 is a rear elevational view thereof; FIG. 14 is a left side view thereof; FIG. 15 is a right side view thereof; FIG. 16 is a top plan view thereof; FIG. 17 is a bottom plan view thereof; FIG. 18 is a bottom perspective view thereof; FIG. 19 is a top perspective view thereof; FIG. 20 is a second top perspective view thereof; FIG. 21 is a third top perspective view thereof; and, FIG. 22 is a second bottom perspective view thereof; shown with a cooler attached thereto for clarity of disclosure. The portions of the cup holder for seating shown in broken line form no part of the claimed design.

The broken line showing of the cooler illustrates an environmental feature that forms no part of the claimed design. The broken line immediately adjacent to the solid line in FIGS. 8, 9, 19, 20, and 21 depicts the bounds of the claim and forms no part of the claimed design.
